H. B. SETZLER

PROCESS OF TREATING PETROLEUM AND PETROLEUM DERIVATIVES

Filed Oct. 22, 1915

UNITED STATES PATENT OFFICE.

HORACE B. SETZLER, OF COFFEYVILLE, KANSAS, ASSIGNOR TO THE NATIONAL REFINING COMPANY, OF CLEVELAND, OHIO, A CORPORATION OF OHIO.

PROCESS OF TREATING PETROLEUM AND PETROLEUM DERIVATIVES.

Application filed October 22, 1915. Serial No. 57,358.

To all whom it may concern:

Be it known that HORACE B. SETZLER, a citizen of the United States of America, residing at Coffeyville, in the county of Montgomery and State of Kansas, has invented certain new and useful Improvements in Processes of Treating Petroleum and Petroleum Derivatives, of which the following is a specification.

10 This invention relates to an improvement in the art of distilling petroleum; preferably using distillates from petroleum containing natural or normal constituents, and which, under ordinary conditions, and 15 known methods, distill over between temperatures of 450° F. and 675° F. known as gas oil, having a specific gravity of 32 to 34 Baumé. Primarily, my object is to obtain from said distillates, products which 20 under ordinary conditions, distill between temperatures of 80° F. and 350° F. and have a specific gravity of 58 to 60 B.; the properties of which are dissimilar from the properties of the natural constituents. To this 25 end, I provide means for preventing the carbon, freed during the operation, from settling, concentrating and depositing in a semi-crystalline coke form, on the sheets of the still.

30 Hitherto, the art of distilling petroleum, has consisted principally in separating its natural constituents, and grouping them into a series of products applicable for commercial use, gasoline, kerosene, gas oil, lubricating oil and wax, when separated by distillation, and each product grouped separately, constitute natural constituents found in the original mass of crude oil.

35 Distilling under pressure has for its object, the production of low boiling point hydrocarbons; the properties of which are dissimilar from the properties of the hydrocarbons from which they are obtained. Pressure distillation therefore, must not be 40 confounded with the normal atmospheric distillation, because the product sought in pressure distillation, is not a natural constituent of crude, but is a product obtained from the natural constituents, through its 45 subjection both to pressure and heat. Such processes are grounded upon the well known fact that hydrocarbons under these conditions, may be degraded down to permanent gases, liquids and solid carbon. Tempera-

tures ranging from 700° to 800° F. are required for these breaking down re-actions; being those at which the affinity between carbon and hydrogen usually is overcome. Consequently, the carbon must remain in the still, or retort, while liquid or gaseous hydrocarbons pass off. In known methods, the carbon thus extracted from the hydrocarbon, by virtue of its gravity, settles to the bottom of the still, and remains there; the particles growing in mass, concentrate 55 themselves in a layer over the entire bottom. Their presence is dangerous, because of the fact, that it is unsafe to operate a still under pressure with a coating of carbon upon its bottom. Therefore, it is quite essential 60 to the performance of such processes, that some device, or apparatus be provided, whereby the carbon, which splits off, is kept, from depositing and concentrating on the sheets of the still, which fact previously, 65 has been recognized.

70 My process involves the continued abrading and agitating action of a movable member, which I understand augments and continues a colloidal or suspended state of much 75 of the carbon content, whereby the chemical reaction or cracking of the treated hydrocarbons is maintained by catalytic action, or by some action analogous thereto, and the formation of deposited, coke-like carbon 80 is avoided.

85 While my invention by no means is limited thereto, I may readily explain the practice thereof in the treatment of the commercial product of gas-oil; comprising a derivative hydrocarbon whose boiling point ranges 90 between 450° F. and 675° F., with a specific gravity between 32 and 34 Baumé, as obtained from mid-continent crude oil. This 95 is selected as typical and explanatory merely, since the temperatures and specific gravities of other derivatives, subjected to my process and even other gas oils, necessarily will vary materially.

100 The improved process of my invention, may best be explained in connection with the accompanying drawings, wherein:—

Fig. 1 is a diagrammatic view in side elevation, partially broken away, showing apparatus adapted for the practice of my invention, and

Fig. 2 is a similar view in end elevation.

Figs. 3 and 4 are cross-sectional views of

2
stills illustrating the helicoidal cleaner and its adjuncts.

Throughout the drawings, similar parts are indicated by the same character reference.

In Fig. 1, a brick-enclosed furnace is shown, wherein the firing-chamber 1, is separated by the bridge wall 2, from the combustion chamber 3, from which a flue 4 leads 10 to a stack 5, for the purpose of carrying off the products of combustion. The furnace is provided with a firing door 6, through which fuel is passed into the furnace, while the heat from combustion, is applied to the bottom of the cylinder-still 7, which is set over and supported by front and rear end walls, of the furnace and the combustion chamber. The still is provided with manhole 8, a pressure gauge 9, and a thermometer (not 20 shown). A charging inlet pipe 10, enters the still at its top, near the front end; the charging being controlled by valve 11, through which oil is pumped by means of pump 12, receiving its supply from a tank 25 not shown. A vapor line 13, leaves the still near its rear end, and leads to a condenser box 14, which contains condensing coils 15, and beyond the condenser box is a valve 16, connected to a pipe leading to the receiving 30 tank 17; the purpose of which equipment is to carry off, condense and receive the products which distill over.

The still 7, is equipped with a rotating shaft 18, mounted in water-cooled stuffing boxes 19, and fitted with a driving wheel 20. Inside the still, there is attached to the shaft, a helicoidal cleaner 21, of such diameter and length as to engage the lower heated inner periphery of the still 7. This rotated abrading member 21 preferably is equipped with 40 lengths or loops of chains 34 which engage and conform to the bottom portions of the still. At the front and rear ends of said shaft respectively, are water pipes 22, 22', leading from a source (not shown) and entering passages drilled in the ends of the shaft 18, a distance equal, at least, to the length of the shaft inside of the stuffing boxes. A discharge 23 is attached to the still 50 at its bottom, near the rear end, and to which is connected outlet pipe 24, leading through valve 25, to a second condensing box 26, and thence through the pipes 27, inside the box, and out through a valve 28, to 55 a receiving tank 29. A motor 30' furnishes the power for driving the wheel 20, connected to shaft 18.

With this description of convenient apparatus for practicing the same, I will now explain, a process typical of my invention. The cylinder still 7, is charged with gas oil, we may assume, having the characteristics previously explained, and to approximately one half the full volume or capacity of the cylinder; after which valves 11, 25 and 16

are closed. Power is turned on the motor connected with driving wheel 20, which revolves the helicoidal scraper or cleaner inside the still. The still is heated by supplies of fuel passed from time to time through the 70 firing-door 6, into the combustion chamber 3, the products of combustion being directed against the bottom of the still, so that the temperature of the contained oil, rapidly rises, until it has reached about 700° F., at 75 which temperature the pressure begins to rise, and is indicated on the pressure gauge 9.

By the time pressure has reached 100 pounds, the temperature will have risen to approximately 730° F., at which temperature 80 and pressure, carbon begins to split off from the heated hydrocarbons: thereby producing new hydrocarbon compounds dissimilar from the body of gas oil, and having boiling points of 80° to 350° F., and a Baumé gravity of 56 to 58. It will be evident to those skilled in the art, that compounds having boiling points of 80° to 350° F., cannot, by reason of their inherent physical properties, 85 remain indefinitely in the still at the temperature referred to, hence they are permitted to pass out through the vapor line 13, and are condensed in the coil 15 and thence conducted to the tank 17, by control of the valve 16.

I have found that without the use of 90 suitable cleaning, scraping, scouring or agitating means, carbon, at the instant it is freed from its previous combination; being of amorphous character, and settling out of the mass of gas oil, seems to be attracted, or 95 drawn to the heated bottom sheets of the still. Normally these particles of carbon growing together, and agglomerating over the bottom sheet, form a dense coating of carbon, resembling a semi-crystalline form, 105 which would have the dangerous results heretofore explained. By using a helicoid cleaner, continuously revolving inside the still, and engaging the heated lower section of the inner periphery of the cylinder, or 110 its equivalent, the carbon which has been freed from its combination, is kept in an amorphous condition, and suspended throughout the mass of oil. Any carbon, which by chance is attracted or becomes attached to the bottom, cannot remain there, because the blade of the helicoid engaging on the bottom, sweeps the particles of carbon away in its course of travel. Another 115 important function of the helicoid is that of conveying the heat from the bottom sheets of the still, with which it is in constant contact, throughout the body of the hydrocarbon and the vapor space in the still above the liquid. This furthers the process in a 120 marked degree, by reason of the fact that the helicoid, through intimate contact with the still bottom, is very highly heated.

It is important that the still be only partially filled, so that an adequate pressure 125

space shall be afforded at all times above the body of hydrocarbons undergoing treatment. Preferably the still is approximately half filled, and is so maintained during the process, inasmuch as it appears that considerable, if not a large proportion of the reaction takes place among the heated vapors compressed in the upper part of the still. These vapors are subjected to the highly heated moving helicoid, equally with the body of hydrocarbons, whereby their reactive temperature is maintained during the continuing process of my invention, as subsequently set forth herein.

As above stated, hydrocarbons can be degraded down to permanent gases and solid carbon, by the influence of heat and pressure, and by the proper regulation of the same, intermediate products between carbon and permanent gases, can be produced, but as far as I am aware, no device or apparatus previously has been employed to maintain the carbon in an amorphous condition, while the change is progressing. It is apparent then, that the degradation of hydrocarbons, necessarily means the extraction of carbon, which is the clogging element in the successful performance of any pressure operation. This I have overcome by the means referred to.

In practicing my process, the gas oil or other hydrocarbon supplied to the still, is subjected to moderately high temperatures and pressures, and the chemical affinity of its elements being partially overcome, certain of the combined carbon atoms are split off in amorphous condition, and are maintained in minute particles, in that condition by continued agitation. When the chemical affinity between the carbon and hydrogen has been broken, the existing chain of hydrocarbons is opened, and a new series is produced, which cannot remain in the highly heated still, because of the low boiling points. Consequently the new products are permitted from time to time, to pass out through the vapor line.

After the described operation has progressed, until approximately 10% of the volume of gas oil charged into the still, has been converted into other products boiling between 80° to 350° F., and the Baumé gravity of said products is found to range from 56 to 58, as indicated by the hydrometer with samples taken from the end of the pipe entering tank 18, the pump 12 is started. Gas oil thus is continuously pumped in through the line 10, regulated by and through valve 11, entering the still at the front end, at the same time the new products referred to, are conducted off through the vapor line 13. Any convenient device may be used, such as meters 30, 31, to establish the ratio of a constant quantity of gas oil, entering the still at the front end, and a

corresponding quantity of converted products passing off, and collecting in the receiving tank 17.

Having established the quantity entering and leaving the still, the operation is continued until a distillate approximately 50% of the volume has been conducted off, when the oil in the still will have reached approximately 24 Baumé gravity. The valve 25, connected by a pipe to the trap on the bottom, near the near end of the still, is then operated for the purpose of drawing off the contents, either continuously or periodically; measuring it through a meter 32, after the liquid has passed through the coils 27, submerged in the cooling box 26.

In the instance assumed, I have stated that when approximately 50% by volume has been conducted off, the Baumé gravity of the oil in the still will have reached approximately 24, at which gravity I begin to draw off at the rear end of the still, but I wish it understood that the gravity test referred to is not invariable. The figures were used merely to indicate the preferred mode of operation, and I have found, that with the gas oil referred to, I can go as low as 18 B. gravity in the still, with no apparent deposit on its bottom, if the agitation be continued, and the operation proceeds regularly under these conditions.

From the foregoing it will be seen that the described process is capable of indefinite continuation, depending somewhat upon the character of the hydrocarbons treated. The liquid condensed and collected in tanks 17, may be distilled in the ordinary manner, primarily for their gasoline content, while the heavier distillates therefrom, may be mixed with the contents of tank 29, and reintroduced into the still 7, for further treatment, if desired, after the carbon has been allowed to settle out. Connected at 33, is an automatic mechanism, which may be used for controlling the continued practice of the described process, but as these steps form no part of my invention, they need not be further referred to herein.

It is apparent that the mechanism provided, serves continuously to agitate the contents of the still, and such agitation, moreover, is coupled with the repeated scouring and scraping of the bottom of said still; all of which contribute to the retention of the carbon in its amorphous form, and prevent its adherence to the bottom plates of said still. In addition, thereto, the helicoidal blade 21, may be formed of copper instead of steel, and may be substituted or augmented by chains or brushes of any material, adapted to afford catalytic action, and therefore promote the chemical reactions within the still. These further features, however, as well as the precise apparatus herein described, or further set forth

in a co-pending application, Serial No. 58,720, filed October 29, 1915, form no essential part of my present invention.

I find, on the contrary, that in conducting my process under commercial conditions, it is not necessary to resort to any outside or foreign catalytic agents, due to the combined action of the moving member and the colloidal or suspended carbon in the gas oil under treatment. The exact nature of such action is not clearly understood, but it is my belief that a marked catalytic property is obtained through maintaining the separated carbon in a colloidal state. The continued abraiding and agitating action to which the inner still walls and still contents are subjected, obtain most favorable conditions for the formation of and preservation of this desirable suspended or colloidal condition. The colloidal carbon is substantially maintained in its state of suspension by the action of the moving member, and prevented from assuming its crystalline form wherein it would lose its properties as an agent to assist in the action upon the unchanged gas oil, and would adhere to the bottom sheets of the still.

Figs. 3 and 4, respectively, are cross-sectional views which illustrate certain specific auxiliary apparatus for augmenting the agitating and scouring means afforded by the helicoidal blade. In Fig. 3, said blade and supporting shaft are shown mounted slightly eccentric to the axis of the still, for the purpose of scraping only the heated bottom portions; said blade being given some play by reason of its loose attachment to the shaft. In Fig. 4, the action of the plate 21, is augmented by chains 34, attached thereto at intervals, thereby permitting its loops to drag over the heated bottom. The shaft may be concentric, if desired, but sufficient play is provided with respect to the scraping, scouring or agitating members, so that the heated bottom portions of the still, in any event, are subjected to such action as will prevent the deposit of the separated carbon particles. Obviously, other means may be employed for accomplishing these actions or functions, and my process or method of treating hydrocarbons may properly be said to be independent of such means particularly shown and set forth herein.

Having now described the preferred method for practicing said invention, I claim as new, and desire to secure by Letters Patent, the following:

1. A process for treating petroleum or its derivatives, which consists in introducing the same to a sealed retort, establishing and maintaining therein a temperature and pressure for cracking a gasoline content therefrom, and meantime subjecting the interior of the retort to the action of an abrading

and agitating movable member, whereby carbon is separated and maintained in a suspended state and the reaction is furthered, substantially as set forth.

2. A process for treating petroleum derivatives of relatively high boiling points, which consists in conducting pressure distillation under conditions of high temperature, sufficient partly to split out the carbon atoms, subjecting the same meantime to mechanical action and the sealed container to continual abrasion for preventing the deposit of said carbon and effecting the even distribution of heat, substantially as set forth.

3. A process for producing gasoline from gas oil which consists in heating the liquid at temperatures approximating 700° F. under moderate pressures in a sealed still structure; meantime maintaining the freed carbon in a state of suspension and subjecting the liquid and the pressure space above it to the action of a highly heated moving member, withdrawing the newly formed hydrocarbons and supplying proportionate quantities of gas oil, substantially as set forth.

4. A process for treating petroleum or its derivatives, which consists in conducting pressure distillation thereof under conditions insuring a relatively large pressure space in the container, meantime maintaining the freed carbon in finely divided state and suspension, while subjecting the treated derivatives and the container to the action of a scouring moving member and withdrawing the newly formed hydrocarbons from the container, substantially as set forth.

5. A process for treating petroleum or its derivatives which consists in conducting pressure distillation thereof in a sealed still maintained substantially half full of the hydrocarbons undergoing treatment, meantime maintaining any freed carbon in suspension while subjecting said hydrocarbons and the heated portions of the still to the action of a moving member, withdrawing the products of pressure distillation, and introducing to the still from time to time, corresponding quantities of said hydrocarbons, substantially as set forth.

6. A process for extracting carbon from gas-oil to produce gasoline, which consists in subjecting the gas-oil to pressure-distillation in a volume maintained substantially constant under conditions involving a pressure of from 50 to 100 pounds, temperatures of from 700° to 750° F., within a highly heated pressure space approximately double the volume of gas-oil under treatment; meanwhile subjecting the gas-oil and its vapors within the pressure space to a moving and highly heated member, and scouring the bottom of the containing still, substantially as set forth.

7. A process for treating petroleum or its derivatives, which consists in introducing the same to a sealed retort, in volume approximately one-half its total contents, establishing and maintaining therein a temperature and pressure for cracking a gasoline content therefrom, and meantime subjecting the interior of the retort to the action of an abrading and agitating movable member, whereby carbon is separated and maintained in a suspended state and the reaction is furthered, substantially as set forth.
8. A process for extracting carbon from petroleum derivatives to produce lighter distillates thereof, which consists in heating said derivatives above 700° F., under pressure within a relatively large pressure space, meantime maintaining the freed carbon in a state of suspension, scouring the heated portions of the still, and supplying fresh quantities of the petroleum derivatives as the lighter distillates are withdrawn, substantially as set forth.
9. A process for extracting carbon from gas-oil to produce lighter distillates such as gasoline, which consists in heating said gas-oil to temperatures ranging from 700° to 750° F., under pressure approximating 50 to 100 pounds within a free pressure space proportioned to the volume of liquid treated, meantime maintaining the freed carbon in finely sub-divided suspension, scouring the heated portions of the still, and supplying fresh quantities of the gas-oil as the lighter distillates are withdrawn, substantially as set forth.
10. A process for producing gasoline, which consists in subjecting suitable hydrocarbons of higher boiling points to pressure distillation under conditions of pressure approximating 100 pounds per square inch and temperatures ranging from 700° F. to 750° F., within a pressure space affording material expansion for the vapors, meantime subjecting the hydrocarbons and vapors to a moving highly heated member and scouring the directly heated portions of the container to prevent adhesion of extracted carbon, substantially as set forth.

In testimony whereof I do now affix my signature in the presence of two witnesses.
